RAIL

Filed Oct. 12, 1929

George R. Douglas. INVENTOR.

BY

BY Ross Donnelly
ATTORNEY.

UNITED STATES PATENT OFFICE

GEORGE R. DOUGLAS, OF DETROIT, MICHIGAN

RAIL

Application filed October 12, 1929. Serial No. 399,380.

My invention relates to a new and useful improvement in a rail and particularly the meeting ends of rails which are placed in alignment to serve as trackage over which 5 rolling stock may be drawn.

It is an object of the present invention to provide rails with abutting ends so arranged and constructed as to permit of expansion and contraction with ease and with a minimum displacement of the rails resulting 10 from expansion and contraction.

Another object of the invention is the provision of rails with abutting ends so arranged and constructed that upon expansion 15 and contraction a smooth and even bearing surface will be presented to the rolling stock at all times.

Another object of the invention is the provision of rails with abutting ends cut diagonally and placed in engagement with each other, so arranged and constructed that as expansion and contraction takes place, the rails will move relatively to each other laterally.

25 Other objects will appear hereinafter.

The invention consists in the combination and arrangement of parts hereinafter described and claimed.

The invention will be best understood by 30 a reference to the accompanying drawings which form a part of this specification, and in which,

Fig. 1 is a fragmentary perspective view of a rail embodying the invention.

35 Fig. 2 is a sectional view taken on line 2-2 of Fig. 1.

Fig. 3 is a sectional view taken through the invention on line 3-3 of Fig. 2.

The rails with which the invention is used 40 are throughout their main body portion of the usual type comprising the base flanges 8 and 9, the web 10, and the ball 11. The ends of these rails are cut on the diagonal line 12, as clearly seen in Fig. 1, the diagonally extending side faces of the rails at 45 the abutting ends being, when the rails are placed in operative position, in engagement with each other.

The portion of the rails which is formed 50 with the diagonally extending face is con-

structed slightly different from the conventional type, particularly as to the web. The web 13 of one portion is spaced apart from the web 14 of the other portion so that these diagonally extending faces meet but at the 55 base portion 15 and the ball portion 16, a chamber 17, thus being provided between the webs 13 and 14. This construction is effected by cutting a groove or recess out of the face of the web. The purpose of such an 60 arrangement is to reduce to a minimum the bearing area of the diagonally extended portions of the rails so that in their movement in response to expansion and contraction, a minimum resistance will be effected. Furthermore, by engaging the rails at this 65 minimum area in the event of the bearing faces becoming rusted, or otherwise roughened, a minimum amount of labor is required in order to remove the roughening or rust or 70 otherwise give a polished and smooth surface to its bearing faces.

In operation, after the abutting ends of the rails have been placed in cooperative position, as shown in Fig. 1, bolts 18 are projected through openings formed in the web portion 13, these openings being of such size as to snugly accommodate the bolts 18. They also project through slots 19 formed in the web portion 14. Spanning these slots 75 19 and forming collars for the bolts 18 are spring plates 20 which are placed under tension upon threading of the nuts 21. Bolts 22 are similarly projected through openings formed in the web portion 17 and extended 80 through slots 19' and formed in the web portion 13, similar spring plates 20' serving as collars for these bolts and being placed under tension by tightening of the nuts 21'.

It is evident that the joint of the rail extends through the distance which the rails overlap and the portion of each of the rails which is overlapped by the other may be considered the joint portion of the rail. Formed in the flange portion 23 of the joint 90 portion of one of the rails are elongated slots 24 which are inclined to the longitudinal axis of the rail extending slightly inwardly at one end toward the web. Formed in the flange 28 at the joint portion of the opposite 95 rail are elongated slots 25 which are inclined to the longitudinal axis of the rail extending slightly inwardly at one end toward the web.

rail are similar elongated slots 27 which are also inclined to the longitudinal axis of the joint portion and extended parallel to the slots 24.

Driven through these slots into the tie 29 or other material which forms the roadbed are suitable spikes or retaining members 30. These spikes 30 serve to retain the rails in position on the roadbed while their mounting in the slot effects a movement of the rail joints during expansion and contraction which assures a minimum surface over which the rolling stock may pass and which affords an even bearing surface for the rolling stock. As expansion takes place and the rails move into a larger overlapping relation, the flange 23 moving, in the view shown in Fig. 1, toward the left, will be operated upon by the fastening members 30. These members which project through the slots 24 will have a tendency to move the thin end of this rail on which the flange 23 is formed outwardly. A similar movement is effected by the slots formed in the flange 28 so that as expansion and contraction takes place, the diagonally extended faces will always remain in close engagement with each other, thus eliminating a crack on the upper surface of the ball so that an uninterrupted surface for the rolling stock to pass over is effected. Also through this movement effected by the retaining members operating in the slots 24 and 27, an easy movement of the rail ends into a larger overlapping relation, or the reverse, becomes possible.

In use, these diagonally extended rail ends may be formed on the ends of rails of substantially standard length or if desired, these overlapping ends may be provided at intervals, the ends of the intermediate rails being formed as desired, and when abutted together, welded, as in this form of construction, contraction and expansion may be compensated for at the joint for a long expanse of rail.

While I have illustrated and described the preferred form of my invention, I do not wish to limit myself to the precise details of structure shown, but desire to avail myself of such variations and modifications as come within the scope of the appended claims.

Having thus described my invention, what I claim as new and desire to secure by Letters Patent is:

1. A rail of the class described, comprising: a main body portion having a diagonally extended end, the face thereof lying in a vertical plane; and a flange on said main body having a plurality of elongated slots formed therein, at the portion thereof lying within the marginal limits of said diagonally extended face, and inclined to the longitudinal axis of said main body in one direction.

2. A rail joint of the class described comprising: a pair of overlapping rails, each of

said rails having at its overlapped portion a diagonally extended face lying in a vertical plane engaging the diagonally extending face of the cooperating rail; a base flange projecting outwardly from the outer side of each of said rails at said overlapping portion; and means operable on the base flange of said rails inwardly of the outer edges thereof for moving the same laterally of each other upon expansion and contraction.

3. A rail joint of the class described, comprising: a pair of overlapping rails, each of said rails having at its overlapped portion a diagonally extending face lying in a vertical plane engaging the diagonally extending face of the cooperating rail; a base flange projecting outwardly from the outer side of each of said rails at said overlapping portion, each of said flanges having at the overlapped portion elongated slots extended at an inclination to the longitudinal axis thereof, the slots at one side being in a direction of inclination opposite to those at the opposite side.

In testimony whereof I have signed the foregoing specification.

GEORGE R. DOUGLAS.
